FISHERMAN'S SHOE

Leon L. Martuch, Midland, Mich., assignor to Scientific Anglers Inc., Midland, Mich.

Filed Jan. 30, 1970, Ser. No. 21,155

Term of patent 14 years

Int. Cl. D2—04

U.S. Cl. D2—310

FIG. 2

FIG. 1 is a front perspective view of a fisherman's shoe embodying my new design.

FIG. 2 is a rear perspective view thereof showing the shoe in a partially opened position.

I claim:

The ornamental design for a fisherman's shoe, substantially as shown.
